UNITED STATES PATENT OFFICE.

JOHN W. HYATT, OF NEWARK, NEW JERSEY, ASSIGNOR TO THE AMERICAN EXTRACTOR COMPANY, OF SAME PLACE.

JUICE-EXTRACTOR.

SPECIFICATION forming part of Letters Patent No. 416,106, dated November 26, 1889.

Application filed February 18, 1889. Serial No. 300,233. (No model.)

To all whom it may concern:

Be it known that I, JOHN W. HYATT, a citizen of the United States, residing at Newark, Essex county, New Jersey, have invented certain new and useful Improvements in Juice-Extractors, fully described and represented in the following specification and the accompanying drawings, forming a part of the same.

This invention relates to apparatus for extracting from disintegrated vegetable materials their liquid or soluble constituents by confining the material operated upon in a chamber, herein called a "compression-chamber," and therein subjecting it to compression between a pervious plunger, herein called a "compressing-screen," and a body of liquid, herein called a "liquid anvil," contained in a reservoir which forms a closed continuation of the said compression-chamber.

The accompanying drawings of apparatus adapted for the desired purpose illustrate one form in which a horizontally-reciprocating compressing-screen is employed and another form in which a vertically-reciprocating compressing-screen is employed, the principle of operation being the same in both cases.

The drawings are as follows: Figures 1, 2, and 3 are respectively a top view, a longitudinal vertical section, and an end elevation, showing a form of apparatus in which there is employed a horizontal compression-chamber, one end of which is connected with an anvil-chamber, which is arranged beneath the compression-chamber and is provided at each end with a tight-fitting removable door. Fig. 4 is a top view showing the portion of the end of the compression-chamber in which the compressing-screen reciprocates, the opposite end of the compression-chamber being represented as broken away. Fig. 5 is a longitudinal section taken through the plane indicated by the line xx on Fig. 4. Fig. 6 is a transverse section taken through the plane indicated by the line yy on Fig. 5. Fig. 7 is a central vertical section of a form of apparatus employing a vertical compression-chamber arranged at the top of a bottle-shaped anvil-chamber.

Referring to the drawings, it will be seen that Figs. 1, 2, and 3 represent a compressing

apparatus composed of a horizontal cylinder A, one end of which is connected by the downwardly-extending flaring goose-neck a with the cylindrically-shaped anvil-chamber B, provided with the tight-fitting removable heads C C, which are held against the ends of the cylinder B by means of the longitudinal bolt D.

A service-pipe E is provided for supplying the chamber B with the liquid which is to serve as the liquid anvil.

In the end of the cylinder A opposite that connected with the anvil-chamber B is the plunger F, to which reciprocating motion is imparted by means of the double link G from the crank H of the rotating driving-wheel I. The working end of the plunger has seated upon it a series of sieves or strainners F', as symbolically represented in cross-section in Fig. 5. In the rear of the sieves the longitudinal passages f in the plunger afford paths of escape for the liquid products of compression into the transverse channel f' , and thence into the longitudinal channel f'' , found in the plunger F. The liquid products of compression are thus conducted to the semi-cylindrical extension of the cylinder A, which constitutes the discharging-trough J, from the end of which they fall into a tank suitably placed to receive them.

The plunger F, provided with the passages described and with the strainners F', is made to perform the functions both of a compressor and of a screen, and is hence herein called the "compressing-screen."

A feed-opening K is formed in the upper side of the cylinder A, through which the masses of disintegrated material to be operated upon are fed into the cylinder in front of the compressing-screen. The portion of the cylinder A into which the disintegrated material fed through the feed-opening K is driven by the working-strokes of the compressing-screen constitutes the compression-chamber.

In the form of apparatus represented in Fig. 7 the compression-chamber is a vertical cylinder A', erected upon the top of the bottle-shaped anvil-chamber B', which is pro-

- vided at the bottom with a removable water-tight door C'. At its upper end the cylinder A' is provided with a flaring mouth K', which constitutes the hopper for feeding in the fiber which is to be compressed. In this case the vertically-reciprocating plunger F² is wholly withdrawn from the cylinder A' at every upward stroke, and during its downward or working stroke the perforated head f³ of the plunger drives into the upper end of the cylinder the charge of fiber which may have been fed into the hopper K'. The convergent walls of the hopper K' are perforated, as shown, and the perforated portion 10 of the hopper is provided with a jacket J', to which is attached a discharge-pipe j. The liquid products of compression compelled to exude through the mass of compressed fiber and through the perforations in the plunger 15 at each downward or working stroke thereof flow into the jacket J', from which they are conducted by the pipe j to the receiving-tank j'.
- The anvil-chamber may be provided with 20 a pressure-gage L and with a suitable relief-valve M, as illustrated, for example, in Fig. 7.
- In operation, in either of the forms of apparatus described, the masses of disintegrated material successively fed into the compression-chamber are by the working-strokes 25 of the compression-screen compressed into a succession of wads, by the collection of which a plug is formed which closely fits the compression-chamber. This plug is supported 30 against the thrust of the compressing-screen by the fluid composing the liquid anvil, against which it bears. A certain portion of this fluid is necessarily displaced as each successive wad is added to the plug, and as the plug 35 is driven toward the anvil-chamber the displaced liquid is compelled to exude through the plug as its only avenue of escape. By being thus brought into enforced contact with the soluble constituents of the plug the 40 displaced liquid dissolves them, and at the same time drives before it any liquid which it finds already contained in the plug. As has been explained, the liquid products of compression escape through the compressing-screen and are ultimately conducted into 45 a suitable receiving-tank. The exhausted material composing the end of the plug toward the liquid anvil falls into the anvil-chamber, from which it is removed from time 50 to time, as may be required, by opening or detaching the removable head C or door C', with which the anvil-chamber is provided. The machine will usually be brought to rest for this purpose; and after the exhausted material has been removed, the head C or door 55 C' replaced, and the anvil-chamber again filled with liquid the machine will again be set in motion and the compressing opération resumed.
- 60 The gage L indicates the pressure in the anvil-chamber when the apparatus is at work,

and it will hence be seen that the feeding of the material and the stroke of the plunger may be varied according to the indications of the gage, so as to produce any desired pressure, and that the valve M will serve as a safety-valve, which will relieve the pressure if it becomes unduly excessive. 7c

Apparatus of the character described is adapted for the extraction of the soluble constituents of comparatively dry substances—such as hops and drugs—and also for the extraction of the soluble constituents and the natural juices of more moist material, such as apples, beets, sugar-cane, &c. 80

What is claimed as the invention is—

1. In an extracting apparatus, the combination, as herein set forth, of a reservoir for containing a body of liquid which is to serve as a liquid anvil, a compression-chamber forming the mouth of said reservoir, a compressing-screen, and means for reciprocating said compressing - screen in said compression-chamber, as and for the purposes described. 85

2. In an extracting apparatus, the combination, as herein set forth, of a compression-chamber, a compressing-screen reciprocating therein, a feed-opening for the successive feeding into said compression-chamber of bodies of the material to be operated upon, and a reservoir forming a closed continuation of said compression-chamber extending below the level thereof, as and for the purposes described. 90

3. In an extracting apparatus, the combination, as herein set forth, of a compression-chamber supplied intermittently with the material to be operated upon and having a feed-opening in one side, a hopper applied to said feed-opening, a compressing-screen reciprocating in said compression-chamber past the said feed-opening, and a reservoir connected with the discharge end of said compression-chamber and forming a closed continuation thereof, as and for the purposes described. 100

4. In an extracting apparatus, the combination, as herein set forth, of a compression-chamber, a compressing-screen reciprocating therein, and a reservoir connected with the discharge end of said compression-chamber and forming a continuation thereof of greater diameter than the diameter of said compression-chamber, as and for the purposes described. 115

5. In an extracting apparatus, the combination, as herein set forth, of a compression-chamber, a compressing-screen reciprocating therein, a reservoir connected with the discharge end of said compression-chamber and forming a closed continuation of said compression-chamber, extending below the level thereof, and a tight-fitting removable door applied to said reservoir, as and for the purposes described. 120

6. In an extracting apparatus, the combination, as herein set forth, of a compression-chamber, a compressing-screen reciprocating

therein, a reservoir connected with the discharge end of said compression-chamber and forming a closed continuation thereof, journal-bearings erected upon the said reservoir, 5 a crank-shaft seated in said bearings, and a link for transmitting power from said crank-shaft to the stem of said compressing-screen for the purpose of imparting reciprocating motion thereto.

In testimony whereof I have hereunto set my hand in the presence of two subscribing witnesses.

JOHN W. HYATT.
